UNITED STATES PATENT OFFICE.

CHARLES W. FAITOUTE, OF SUMMIT, NEW JERSEY.

TIRE.

No. 816,225.

Specification of Letters Patent.

Patented March 27, 1906.

Application filed December 27, 1904. Serial No. 238,444.

To all whom it may concern:

Be it known that I, CHARLES W. FAITOUTE, a citizen of the United States, residing at Summit, in the county of Union, State of New Jersey, have invented a certain new and useful Tire, of which the following is a specification.

The objects of this invention are to provide a cushioned tire of improved construction, to secure resiliency, together with lightness and cheapness of construction, and to obtain other advantages and results, some of which may be referred to hereinafter in connection with the description of the working parts.

The invention consists in the improved cushioned tire and in the arrangements and combinations of parts of the same, all substantially as will be hereinafter set forth and finally embraced in the clauses of the claim.

Referring to the accompanying drawings, in which like numerals of reference indicate corresponding parts in each of the several figures, Figure 1 is a cross-section of one form of my improved tire. Fig. 2 is a longitudinal central section of the same as upon line *x*, Fig. 1. Fig. 3 is a cross-section of another form of the invention; and Fig. 4 is a central longitudinal section as upon line *y*, Fig. 3, showing a further modified construction.

In said drawings, 2 indicates the outer casing or shoe of the tire, made of any suitable material which is flexible but not elastic and adapted to sustain heavy wear. This outer casing incloses and holds in position the inner cushioning devices, which will next be described.

At the side of the tire adapted to lie next the felly or body portion of the wheel is arranged a band of rubber 3, transversely rounded at its bottom 4 to fit the casing 2 and being preferably curved transversely at its top, as at 5. This strip about half fills the casing and may be chambered or recessed, as at 6, if desired. Above the said band 3 is arranged a transversely concavo-convex strip 7, which reaches from side to side of the casing and rests at its edges upon the band 3, the middle portion of said strip 7 being separated from the band 3 by a space 8. Above the strip 7 described is a second strip 9, rounded at its outer side to fit the casing 2 and being at its inner side longitudinally grooved in any suitable manner to give greater resiliency. Preferably said grooves are round-bottomed, as shown at 10 in Figs.

1 and 2, but may, if desired, be of other shape, such as angular at their bottoms, as at 11 in Figs. 3 and 4.

It will be understood that the casing binds the band and strips 3, 7, and 9 together, as shown in the drawings, while at the same time their resiliency holds them apart to form spaces between until compressed by a load.

Obviously the detail formation of the strips may be varied and their arrangement changed without departing from the spirit and scope of the invention. For instance, in Fig. 3 I have shown a bottom band 12 like the one, 3, above described in connection with Fig. 1, and with said bottom band or strip two upper strips 13 14, which have the angular grooves in their under surfaces. This construction is particularly adapted for heavy loads, although any of the strips can be varied to meet different conditions by changing their thickness. So far as above described these various strips are continuous with respect to the periphery of the wheel, as will be understood; but obviously under some conditions one or more of them might be divided transversely into short sections 15, separated by transverse open spaces 16, as shown in Fig. 4.

Other detail modifications might also be made without departing from the spirit and scope of the invention.

Having thus described the invention, what I claim as new is—

1. A cushion-tire comprising an outer casing, an interior band filling the part of said casing adapted to lie against the wheel, and resilient superposed members between said casing and the band, said members being transversely concavo-convex.

2. A cushion-tire comprising an outer casing, an interior band filling the part of said casing adapted to lie against the wheel, and resilient superposed members between said casing and the band, said members being transversely convex on their outer surfaces and longitudinally grooved at their inner surfaces.

3. A cushion-tire comprising an outer casing, an interior band filling the part of said casing adapted to lie against the wheel, and resilient superposed strips extending through the casing above said band, said strips being transversely concavo-convex.

4. A cushion-tire comprising an outer casing, an interior band filling the part of said

casing adapted to lie against the wheel, and
resilient superposed strips extending through
the casing above said band, said strips being
transversely convex on their outer surfaces
5 and longitudinally grooved at their inner sur-
faces.

5. A cushion-tire comprising an outer cas-
ing, an interior band filling the part of said
casing adapted to lie against the wheel, and
10 transversely disposed and curved resilient

pieces arranged between the band and cas-
ing, said pieces providing open spaces be-
tween themselves.

In testimony whereof I affix my signature
in presence of two witnesses.

CHARLES W. FAITOUTE.
